UNITED STATES PATENT OFFICE.

LESLIE P. GREEN, OF CHICAGO, ILLINOIS.

SCRAPER.

Application filed June 9, 1921. Serial No. 476,190.

To all whom it may concern:

Be it known that I, LESLIE P. GREEN, a citizen of the United States, and a resident of the city of Chicago, county of Cook, and State of Illinois, have invented certain new and useful Improvements in Scrapers, of which the following is a specification.

My invention relates to improvements in scrapers especially adapted for use in excavating work and has for its object the improvement of an improved construction of this character which is simple of construction and highly efficient in use.

Other objects will appear hereinafter.

15 The invention consists in the combinations and arrangements of parts hereinafter described and claimed.

The invention will be best understood by reference to the accompanying drawings 20 forming a part of this specification, and in which,

Fig. 1 is a perspective view of a scraper embodying the invention,

Fig. 2 is a side view of the same,

25 Fig. 3 is a transverse section taken substantially on line 3—3 of Fig. 2 and showing the scraper as in actual operation.

Fig. 4 is a side view of a modified form of construction and,

30 Fig. 5 is a section taken on line 5—5 of Fig. 4 and showing the scraper in position of use.

The preferred form of construction as illustrated in the drawings, comprises two 35 scraping members secured together in forwardly divergent relation to each other, said scraping members being substantially in contact and secured together at their rear ends and diverging forwardly therefrom. Each of said scraping members is 40 preferably made of sheet steel and comprises a substantially vertical upper portion 4 and an inwardly and downwardly inclined lower portion 5 as indicated. Said 45 scraper members are rigidly secured together at their rear ends where they are provided with a vertical lip or flange 6 having two perforations 7 for the reception of a clevis 8 to which cable 9 is attached. At their lower edges the scraper 50 portions 5 are reinforced by wear plates 10 as shown. At their forward portions the scraping members are provided with forwardly extending vertical keel plates or 55 guides 11 secured to the forward edges of portions 4 and also secured to the forward upper edges of the portions 5 along lines 12 as indicated. The forward edges of the guide plates 11 are provided with a plurality of openings 13 for the reception of clevises 14 for attachment to the cables 15 as shown and cover portion 16 is arranged across the upper portions of the sides 4 and provided with vertical flanges 17 arranged against the inner sides of the members 4 and secured thereto by means of bolts 18. The bolt holes for the bolts 18 are so arranged that the cover portion 16 may be removed and reversed in position as indicated in Fig. 3 and whereby the capacity 70 of the scraper may be varied.

In use the scraper is utilized by drawing the same in one direction over the area to be excavated by means of the forward cables 15. During such movement 75 the scraping portions 5 will dig up the earth or other material and gather the same in the enclosure between the scraping members. When this enclosure becomes substantially filled, the cover portion 16 will 80 rest and ride upon the material therein, thus in effect, elevating the scraper from digging contact and preventing any further digging. For this purpose the cover member 16 should be of sufficient area and extent to cause this riding action which will 85 prevent the useless expenditure of energy in digging up material which cannot be contained in the scraper, the cover member 16 also serving as an efficient brace for the 90 scraping members 4—5. When the scraper thus filled with material is brought to the position desired, the direction of travel thereof is reversed by the slackening away on cables 15 and drawing on cable 9. Owing 95 to the fact that the enclosure between the scraping members is substantially open at its front and bottom, the contained material will be deposited at this point and the scraper is then returned for a new load. 100 By removing the cover portion 16 and reversing the same in position, the capacity of the scraper may be varied to the extent of the depth of the flanges 17. The keel or guide plates 11 serve to maintain the 105 travel of the scraper in a substantially straight forward direction preventing side swerving, stiffen the construction, and also tend to hold the load or charge therein during forward travel.

110 In the modified form of construction illustrated in Figs. 4 and 5, the scraping

members 19 are made flat and are arranged to slope inwardly and downwardly from their tops to their bottoms.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A scraper comprising scraping members associated together to form the sides of an enclosure substantially open at the front and bottom; and a cover portion for said enclosure vertically adjustable with relation to said scraper members and adapted and arranged to rest upon material gathered between said scraper members and cause said scraper to ride upon said material when substantially filled, substantially as described.

2. A scraper comprising scraping members having inwardly and downwardly inclined lower portions; and a cover portion extending over the space between said scraping members to rest upon material gathered thereby and cause said scraper to ride upon said material when substantially filled, substantially as described.

3. A scraper comprising scraping members arranged in forwardly divergent relation to each other; and a cover portion extending between the upper portions of said scraping members to rest upon material gathered between them and cause said scraper to ride upon said material when substantially filled, substantially as described.

4. A scraper comprising scraping members arranged in forwardly divergent relation to each other; and a cover portion extending between the upper portions of said scraping members and adjustably secured thereto to rest upon material gathered between said scraping members and cause said scraper to ride upon said material when substantially filled, substantially as described.

5. A scraper comprising scraping members having substantially vertical upper portions and inwardly and downwardly inclined lower portions; and a cover portion extending between the upper portions of said scraping members to rest upon material gathered between them and cause said scraper to ride upon said material when substantially filled, substantially as described.

6. A scraper comprising scraping mem-

bers arranged in forwardly divergent relation to each other and having substantially vertical upper portions and inwardly and downwardly inclined lower portions; and a cover portion extending between the upper portions of said scraping members and adjustably secured thereto to rest upon material gathered between said scraping members and cause said scraper to ride upon said material when substantially filled, substantially as described.

7. A scraper comprising scraping members associated together to form the sides of an enclosure substantially open at the front and bottom; and a cover portion extending between the upper portion of said scraping members, said cover portion being provided with vertically turned flanges fitting against the inner sides of said scraping members and detachably secured thereto, said cover member being reversible between said scraping members, substantially as described.

8. A scraper comprising scraping members arranged in forwardly divergent relation to each other and having substantially vertical upper portions and inwardly and downwardly inclined lower portions; and a cover portion extending between the upper portions of said scraping members, said cover portion being provided with vertically turned flanges at its sides fitting against the inner sides of said scraping members and detachably secured thereto, said cover member being reversible between said scraping members, substantially as described.

9. A scraper comprising scraping members arranged in forwardly divergent relation to each other; and a cover portion extending between the upper portions of said scraping members and for substantially the full length thereof, substantially as described.

10. A scraper comprising scraping members having inwardly and downwardly inclined lower portions; and a cover member extending between the upper portions and substantially the full length of said scraping members, substantially as described.

11. A scraper comprising scraping members arranged in forwardly divergent relation to each other and having substantially vertical upper portions and inwardly and downwardly inclined lower portions; and a cover member extending between the upper portions and substantially the full length of said scraping members, substantially as described.

In testimony whereof I have signed my name to this specification in the presence of two subscribing witnesses.

LESLIE P. GREEN.
